(57) **CLAIM**

The ornamental design for a foldable cabinet, as shown and described.

DESCRIPTION

FIG. 1 is a front, top and right-side perspective view of a foldable cabinet showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof;

FIG. 8 is a rear, bottom and left-side perspective view thereof;

FIG. 9 is an alternate configuration in another perspective view thereof;

FIG. 10 is an enlarged view, of circled portion 10, of FIG. 1, thereof;

FIG. 11 is an enlarged view, of circled portion 11, of FIG. 2, thereof;

FIG. 12 is an enlarged view, of circled portion 12, of FIG. 7, thereof; and,

FIG. 13 is an enlarged view, of circled portion 13, of FIG. 8, thereof.

The broken lines throughout the drawing figures depict portions of the foldable cabinet that form no part of the claimed design.

The dot-dash broken lines depict the boundaries of the FIGS. 1, 2, 7, 8 and 10-13 enlargement that forms no part of the claimed design.

1 Claim, 13 Drawing Sheets
